BICYCLE FRAME

Charles F. Voytech, 208 S. La Salle St.,
Chicago, Ill. 60604

Filed Feb. 16, 1967, Ser. No. 5,840

Term of patent 14 years

(Cl. D90—8)

FIG. 1 is a side elevational view of the bicycle frame;
FIG. 2 is a plan view of the bicycle frame of FIG. 1;
FIG. 3 is a bottom view of the bicycle frame of FIG. 1;
FIG. 4 is a rear elevational view of the bicycle frame of FIG. 1, looking toward the right in FIG. 1, and
FIG. 5 is a front elevational view of the bicycle frame of FIG. 1, looking toward the left of FIG. 1.

The broken lines on FIGS. 1-5 are disclosed for illustrative purposes only, to show how the frame is used in a bicycle.

I claim:

The ornamental design for a bicycle frame, substantially as shown and described.
